UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPET.

Specification forming part of Design No. **11,496**, dated November 4, 1879; application filed August 1, 1879.
[Term of patent 3½ years.]

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration, forming a part of this specification.

The design consists of a groundwork of pure Grecian style, formed in differently-ornamented alternating squares 1 2, arranged in longitudinal and transverse rows, and floral designs resting on said groundwork.

The floral designs are natural and free-hand, and are arranged to give the effect of festoons or an irregular net-work of flowers, as shown. The heavier portions of the floral designs give almost continuous wave effects of festooned flowers diagonally and longitudinally of the carpet.

I am aware of Design Patent No. 7,339, showing floral designs on a ground ornamented by rectangular and other figures. In said patent, however, the floral designs are stiff

and of the conventional form, presenting a marked contrast to mine, which are natural, and known as "free-hand."

Again, in said patent the ground is ornamented by squares, which are interlaced, and are, therefore, not independent of each other, while the squares, 1 2, ornamenting the ground in my design are entirely distinct from each other, so that the longitudinal and transverse rows in which they are arranged may be readily followed by the eye, like the tiles in a floor or pavement.

I claim—

The design for a carpet having the Grecian groundwork formed of independent squares 1 2, and the free-hand floral designs resting thereon, and arranged as shown and described.

In testimony whereof I have signed my name to this specification, in the presence of two subscribing witnesses, this 24th day of July, 1879.

THOMAS J. STEARNS.

Witnesses:

C. F. BROWN,
J. M. SKINNER.
